UNITED STATES PATENT OFFICE

MANUEL C. GARDINE, OF ST. LOUIS, MISSOURI

LOCKABLE KEY RING

Application filed August 13, 1927. Serial No. 212,790.

My invention consists in improvements in key rings whereby the key ring carrying a number of keys may have double hooks overlapping each other in the plane of and within 5 in the inner circle of the body of the ring and may thereby better safeguard the keys and furthermore may be locked against unauthorized removal of the keys.

I obtain this object by means shown in 10 the drawings and now to be described.

Figure 1 is a side elevation of a key ring embodying my invention; Fig. 2 is a side elevation of the incomplete ring at an intermediate stage of its manufacture; Fig. 3 15 is a top view of the same ring and Fig. 4 is a greatly enlarged vertical section through the key ring taken on the line 4—4 of Fig.

1. Similar reference numerals designate like parts in all the views.

20 The body of the ring will preferably be made of round or oval steel wire of suitable gauge.

The steps of forming the ring are substantially as follows:

25 A wire rod of suitable length, varying according to the size of the ring which is to be made, will be bent to the approximate form shown in Fig. 2; an arched member or hook 5 will be formed at one end of the rod and a complementary arched member or hook 6 will be formed at the other end of the rod.

30 The hook 5 will then be swaged by any suitable means to form a flat upper surface 5a; and similarly the hook 6 will be swaged to 35 form a flat under surface 6a. The rod will then be again bent to form a complete circular ring, as indicated by dotted lines in Fig. 2 and when that is accomplished the faces 5a and 6a will lie in close contact with each other and the over-lapping hooks will 40 form a closed loop designated as a whole by the numeral 7.

I have shown and described a key ring made from a round rod, but it is obvious 45 that rods of oval or polygonal cross-section

may be used without departure from my invention.

The arched members 5 and 6 are approximately half the thickness of the rod from which they are formed; the member 5 has 50 a flat face 5a and a terminal part 5b which extends outwardly somewhat beyond the arch of the member 6; and the member 6 has a terminal part 6b which extends outwardly somewhat beyond the arch of the 55 member 5. When the arched members are associated as indicated in Fig. 2 the overlapping parts will lie in the plane of the ring and wholly within the inner circle of the ring.

When the ring is completed the keys will be assembled on the ring in the usual manner. The hasp of a lock 8 of any approved construction may be hooked in the loop formed by the juxtaposed hook-members 60 65 and may be locked to prevent unauthorized detaching of the keys.

It is obvious that a lockable clasp of any suitable known construction may be used instead of the padlock shown in the drawings. A snap hook on the end of a key chain will serve to prevent removal of any 70 keys from the ring so long as the key ring remains attached to the chain.

To isolate any particular key; the loop 75 of the key will be placed in the loop 7 of the ring in the following manner:

The body of the key will be held in one hand and the body of the ring will be held in the other hand. The handle of the key 80 will be placed on one terminal, say the terminal 5b, with the terminal extending through the loop or eye in the handle of the key, and will be pushed along the member 5b which supports it, until the handle of 85 the key turns around the terminal 6b so that the loop of the key surrounds both the lapped lower or inner members of both arches.

Having fully described my invention, 90

what I claim as new and desire to secure by Letters Patent is:

1. In a key holder, the combination of: a resilient main outer loop; and a supplemental inner loop consisting of a pair of hooks having lengthened limb elements, oppositely faced, reduced in thickness, and flattened on adjacent surfaces; said limb elements being overlapped, each with its respective end extended beyond the arch of the other hook, and being held in juxtaposition by the resiliency of the main loop, and adapted to be sprung apart in a direction perpendicular to the plane of the loops, but not circumferentially, to allow the passage of a free key into the supplemental loop, and likewise adapted to be sprung apart to allow the passage of a key from one loop to the other; whereby a selected key can be quickly and securely isolated on the supplemental loop or associated with other keys on the main loop as desired.

2. A lockable key ring of smooth exterior contour, consisting of a main ring of resilient wire closed by overlapping a pair of inwardly turned, integral, arch members of reduced thickness, to form an inner loop of total thickness nowhere greater than the thickness of the main ring; each of said arch members comprising a shank portion of reduced thickness extending forwardly in direct continuation of the body of the main ring, an arch portion curving inwardly, and a terminal limb portion extending backwardly and protruding beyond the bend of the other arch member.

3. In a key ring, the combination of: a solid outer loop; and a smaller inner loop comprising inwardly disposed U-shaped hooks with approximately parallel limbs, overlapped at the limb portions and having the free end of the innermost limb portion of each hook extended beyond the bend of the other hook, whereby to guide the handle of a key between the lapped limbs of the inner loop.

4. A lockable key-holder comprising: a main ring formed from a solid rod bent in a plane; and a pair of overlapping open arch members oppositely directed in said plane and flattened on adjacent sides throughout the extent of overlapping, thereby forming an inner loop; said arch members consisting of flattened stem elements in forward continuation of the main portion of said rod overlapped to close said main ring, bent elements inwardly recurved and singly disposed, and limb elements each overlapping the other and each backwardly extended beyond the bend of the other arch member, whereby the key-holder is adapted to be locked by a hasp linked with said ring through said loop.

5. In a key ring, in combination with an outer loop: an inner loop formed by a pair

of hook elements each comprising limbs and an arch, said inner loop having two lapped portions consisting of the limbs of both hook elements in juxtaposition, and two unlapped portions consisting of the respective arches of the hook elements singly disposed.

In witness whereof I have hereunto signed my name at St. Louis, Missouri, this 4th day of August 1927.

MANUEL C. GARDINE.
